Arthur F. Jenkins,
ATTORNEY

UNITED STATES PATENT OFFICE

CHARLES J. JOLIDON, OF HARTFORD, CONNECTICUT

NAIL TRIMMER

Application filed September 15, 1928. Serial No. 306,169.

My invention relates to the class of devices employed for manicuring purposes in clipping and trimming the nails, and an object of my invention, among others, is the production of a device of this class that shall be simple in construction and particularly efficient and convenient to use.

One form of a nail trimmer embodying my invention and in the construction and use of which the objects herein set out, as well as others, may be attained, is illustrated in the accompanying drawings, in which—

Figure 1 is a side of my improved trimmer.

Figure 2 is a top view of the same.

Figure 3 is a bottom view thereof.

Figure 4 is a view in central lengthwise section crosswise of the pivot.

Figure 5 is an isometric view of the outer member.

Figure 6 is a similar view of the inner member.

In the accompanying drawings the numeral 10 denotes the outer generally channel shaped member of my improved trimmer, 25 and 11 the similarly shaped inner member thereof. These are formed to create a box like structure at the front end so that nail clippings will be caught within this box or receptacle and thus prevented from flying 30 away from the trimmer when in use. To this end the outer member 10 has sides 12 and a bottom 13 with a jaw 14 connecting said sides at the upper ends thereof, thereby forming a head with an opening 15 at its 35 front end. This member is also extended into a handle 16 having sides 17 with beveled file edges 18, these sides creating a groove 19 closed at its outer end. A notched stud 20 is secured to and projects upwardly from the 40 bottom of the groove for a purpose to be hereinafter described.

A nail cleaner 21 is pivotally supported on the outside of the member 10 and has a stud 22 projecting through the bottom of the handle 16 into the groove 19 and a spring 23 surrounding said stud exerts a thrust against a washer 24 secured on the stud to provide for friction to hold the nail cleaner against freedom of movement.

50 The member 11 has a head comprising sides

25, a jaw 26 and a bottom 27 formed as a box-like structure, as in the case of the other member hereinbefore described. This head is of a size to fit within the head 28 on the member 10, and as shown in Figures 1 and 55 4 of the drawings. The jaws 14 and 26 are sharpened and are relatively positioned to form shears by means of which nails may be cut. This member 11 is also extended to 60 form a handle 29 having sides 30 with its edges beveled and formed to correspond with the beveled edges 18 on the member 10, and also having a bottom 31. A sliding catch 32 projects from the bottom of the interior of the handle and has a lip adapted to engage 65 the notch in the stud 20 to hold the handles against separation under the thrust of a spring 33 mounted, as shown in Figure 4, to thrust the handles and also the jaws 14 and 26 apart when not held by engagement of 70 the catch with the stud.

The head of the member 11 is located within the head of the member 10, when the parts are assembled, and said heads are pivotally connected as by a pivot 34 in a manner that 75 will be readily understood and when so connected a box or receptacle is formed by the head and comprising a compartment 35 within which nail clippings will be caught and which will, therefore, be prevented from 80 flying off.

The cleaner 21, or the head of the stud 22 when separately formed from the cleaner, is provided with a recess 36 that is roughened to provide an abrading surface for the purpose of filing the nails, and the head 37 of the catch 32 is also roughened for a like purpose.

It will be noted that the beveled file edges 18, when the handles are closed together, 90 form a groove within which finger nails may be readily and conveniently filed or smoothed off.

In accordance with the provisions of the patent statutes I have described the principles of operation of my invention, together with the device which I now consider to represent the best embodiment thereof; but I desire to have it understood that the device shown is only illustrative and that the in- 100

vention may be carried out by other means and applied to uses other than those above set out.

I claim:

- 5 1. A nail trimmer including two members pivotally united and each comprising a head having registering and overlapping side closing walls and bottom walls forming a compartment to receive clippings, said members also including handles having registering closing side walls to form a hollow extension from said compartment and crossed cutting jaws located in cooperative cutting relation on each of said heads.
- 15 2. A nail trimmer including two channel shaped members each having at one end a transversely extending cutting jaw arranged at right angles to and disconnected from the bottom wall of the channel, means for pivotally uniting said members, means for forcing the cutting jaws towards each other, said members having cooperating portions forming a hollow handle, a stud projecting inwardly from the bottom of one of said handles and having a notch, and a catch slidably mounted on the other handle to engage said notch.
- 30 3. A nail trimmer including two channel shaped members pivotally united and having cooperatively acting transverse cutting jaws supported solely at their ends on the side walls of the members, handles cooperatively arranged on said members, a stud projecting from one handle towards the other, and a catch movably mounted on the other handle to engage said stud to lock the handles against opening movement.
- 35 4. A nail trimmer comprising two members including handle portions and heads in the ends thereof, each head being open on one side and having a band formed by a slot extending across the end, said bands forming cutting jaws, and means for pivotally connecting said members one within the other.
- 45 5. A nail trimmer comprising two channel shaped members each including a handle portion and a head at one end of each handle portion, each head comprising side parts with a band curved lengthwise extending across the end of the head between the side parts, said bands bounding slots extending across the ends of the heads, and means for securing said heads together one within the other.

CHARLES J. JOLIDON.
